UNITED STATES PATENT OFFICE.

EDWIN J. OLSON, OF WHEATON, MINNESOTA.

FOLDING WASHSTAND.

1,325,107.

Specification of Letters Patent. Patented Dec. 16, 1919.

Application filed September 5, 1917. Serial No. 189,823.

To all whom it may concern:

Be it known that I, EDWIN J. OLSON, a citizen of the United States, residing at Wheaton, in the county of Traverse, State 5 of Minnesota, have invented certain new and useful Improvements in Folding Washstands, and I do hereby declare the following to be a full, clear, and exact description of the invention, such as will enable others 10 skilled in the art to which it appertains to make and use the same.

This invention relates to washstands.

The object of the invention is to provide an improved form of folding washstand for 15 use in households and under other circumstances where it is desirable or necessary to dispose of articles of furniture which are used only at brief periods during the day. The washstand of my invention is so constructed that it may be readily folded into a compact bundle and placed in a closet, by a door or other suitable locality which permits of the storage of a flat package.

With the above objects in view, and such 25 others relating to the details of construction, which may hereinafter appear, my invention will now be fully set forth and described, reference being had to the accompanying drawings.

30 In the drawings:—

Figure 1 is a front elevation,

Fig. 2 is a side elevation,

Fig. 3 is a detail sectional view,

Fig. 4 is another detail sectional view,

35 Fig. 5 is a perspective view of a brace rod, and

Fig. 6 is an enlarged fragmentary view showing a further detail of the structure.

Referring more particularly to the drawings, 1 represents a pair of vertical standards which are connected by an upper cross bar 2 and a lower cross bar 3. The upper cross bar 2 is spaced well below the upper ends of the standards 1, so as to provide a 45 clearance for a swinging mirror 4. Said mirror 4 is provided with laterally projected trunnions 5 which operate in brackets 6 extended forwardly from the outer edges of the standards 1.

50 Mounted upon the inner edges of the standards 1 are the forwardly projecting brackets 7 to which are pivoted the rear corners of a shelf member 8. Thus, the brackets 7 extend outwardly beyond the 55 standards 1, and receive therebetween the

corners of the shelf, whose side edges are bound by metal straps 9. The rear ends of the straps 9 are apertured as at 10, over recesses 11 which are cut into the material of the shelf. There are thereby provided 60 sockets within which the heads 12 of the bolts 13 are pivotally received. The threaded ends of the bolts 13 project outwardly from the shelf member 8 and extend beyond the brackets 7 so as to receive the nuts 14. 65

Also, the straps 9 are longitudinally provided with the slots 15 which overlie recesses 16 formed in the edges of the shelf. There is thereby formed guide-ways for the heads 17 which are extended right angularly from the ends of the brace bars 18. The opposite ends of the brace bars 18 are provided with the right angular projections 19 which are threaded to receive the nuts 20 by means of which the projections 19 are 75 secured within brackets 21 fastened to the outer edges of the standards 1 below the shelf 8. By the above described assemblage of parts, a simple and practical folding shelf 80 is provided.

In completing the washstand, a suitable soap dish 22 may be hinged to one standard and a hinged towel rack 23 mounted upon the other standard at suitable height, the towel rack being adapted to be swung inwardly across the standards when the structure is folded. If desired, the upper cross piece 2 may be located just above the upper edge of the shelf 8, when the latter is in its folded position, so that a turn button 24 may be employed to hold the shelf in its upraised position. 85

In the use of the device, it may be either removably hooked to a wall or to any other support, so that it may be stored away when 90 not in use, or else it may be screwed to the wall, and merely folded when it is not required.

What I claim as my invention is:—

A folding article of furniture comprising 100 a supporting frame having upper and lower pairs of perforated brackets, a shelf having a recess and a longitudinal channel in each end face, a plate secured to each end face and having a perforation and a slot 105 registering with the corresponding recess and channel respectively and of lesser widths than said recess and channel, a pair of bolts each disposed with its head in a recess and its stem projecting through the 110

corresponding plate perforation and engaged with a corresponding bracket of the upper pair, a pair of rods each having its ends laterally turned, one laterally turned end of each rod being headed and slidably disposed with its head in a channel and the adjacent turned portion projecting through the corresponding plate slot and pivotally and slidably movable therein, the other

laterally turned ends of the rods being 10 pivotally engaged in the corresponding lower brackets of the frame.

In testimony whereof I affix my signature in the presence of two witnesses.

EDWIN J. OLSON.
